UNITED STATES PATENT OFFICE.

JULIUS A. ZUEHLKE, OF SOUTH BEND, INDIANA, ASSIGNOR TO QUICK ACTION IGNITION COMPANY, OF SOUTH BEND, INDIANA, A CORPORATION OF INDIANA.

SPEED GOVERNOR FOR INTERNAL-COMBUSTION ENGINES.

1,409,639.

Specification of Letters Patent. Patented Mar. 14, 1922.

Application filed August 5, 1918. Serial No. 248,354.

To all whom it may concern:

Be it known that JULIUS A. ZUEHLKE, citizen of the Province of Posen, Germany, residing at South Bend, in the county of St. 5 Joseph and State of Indiana, has invented certain new and useful Improvements in Speed Governors for Internal-Combustion Engines, of which the following is a specification.

10 My invention comprises improvements in speed governors for internal combustion engines and it more especially relates to the features pointed out in the annexed claims.

15 The purpose of my invention is to provide a mechanically operated speed governor of a very sensitive order, that will control the periods of activity of the usual ignition systems against excessive over or under engine speeds.

20 With these and other purposes in view I illustrate in the accompanying drawing such an instance of adaptation as will disclose the broad features without limiting myself to the specific details exemplified 25 thereon.

Fig. 1 is an elevation transverse of the engine shaft of the governor members in assembled relation to the circuit breaker spark plug, etc., the latter being shown diagrammatically.

30 Fig. 2 is a sectional elevation transversely of Fig. 1 showing the assembled relation of the magneto parts with which the governing mechanism may be combined.

35 My invention may be carried into practice in numerous ways that are obvious equivalents of the exemplification instanced in the accompanying drawing without departing from the spirit of the invention.

40 In the adaptation shown the engine shaft 1 supports a field magnet 9 held in a suitable member 8 which may be an enclosed plate with an annular flange around its periphery or it may have spokes or arms connecting the rim to a hub as shown in Fig.

45 2. The rotation of this permanent field magnet adjacent the heads of armature coil 7 that is supported by plate 6 induces periodic impulses in the coil 7. These are 50 centuated by reason of the interruption of the primary winding by the arm 23 of breaker 4 disconnecting contact 24 at the proper moment by a cam 20 whenever it engages the breaker shoe 22. A condenser 5

is connected in parallel with the breaker 55 contacts as usual. The secondary 3 of coil 7 supplies one or more spark plugs 2 under the control of any suitable distributor when applied to multicylinder engines.

Attempts have heretofore been made to 60 produce governors by using single lever devices but with unsatisfactory results because the movement of the cam 20 is inherently too great for a given movement of the governor weight 13, besides beats or pulsations 65 are liable to be set up in a single lever that are not found in compound lever systems. At certain speeds and certain resonating conditions such beats will synchronize with the periods of cam engagement and thus 70 modify the results of the cam action, in some cases producing satisfactory results and in other apparently similar cases, producing entirely negative results.

In the form instanced in the drawing a 75 governor arm 11 is pivoted at 12 to a support 10. This support is attached to the magnet carrier 8 and obviously rotates with it. A weight 13 may be slidable on arm 11 when a set screw 14 will hold it in any desired position, or it may be fastened permanently in duplicate devices after its correct place has been fixed by actual tests or otherwise. The arm 11 has a spring 25 attached at the end opposite to the weight 13 80 and any suitable limit stop may be provided adjacent this end or at any other point to limit the extent of the spring action.

The direct movement of the arm 11 is modified by the link 15 pivoted to the arm 90 at 16 and to the cam lever 18 at 17. The other end of the curved cam lever 18 is pivoted at 21 to a projection 19 that extends out from support 10. Since the cam 20 is placed about midway of the length of the 95 lever 18 it will be seen that the extent of movement of the link 15 will be reduced about one-half thus making a very sensitive device.

The action of the governor is very simple 100 indeed. As the weight 13 moves away from the shaft 1 when the engine speed increases the cam 20 is gently moved toward the shaft center, thus if the action continues, the path of rotation of the cam will be at a shorter 105 radius to the engine shaft 1 and the breaker shoe 22 will not be engaged by the cam hence the required activity of the ignition

circuit will be absent and in consequence one or more strokes of the engine will be minus their impelling impulses and the engine speed will in consequence be lowered, until 5 the cam 20 again moves outward sufficiently far to reengage the breaker shoe 22 when the ignition circuit will again become sufficiently active to fire the engine.

What I claim is,

- 10 1. In speed governors for internal combustion engines, a movable member, a stationary member, an ignition system, connections between the former and the latter, a spring actuated weighted arm carried by 15 the movable member, a cam lever also carried thereby and pivoted thereon at one end, a cam thereon, a connecting link attached to the free end of said lever and pivoted to the weighted arm near its fulcrum, a circuit 20 breaker secured to the stationary member, adjacent the path of travel of the cam, a circuit controlling shoe pivoted to the circuit breaker, and means for automatically moving the cam through the action of the 25 weighted arm to cause the cam to not engage the shoe at certain changes in speed of the rotating member and to periodically re-engage said shoe at other speeds.
2. In speed governors for internal combustion engines, a rotating member, a pivoted projection, a stationary member on which said projection is pivoted, a plurality of interconnected levers carried by the 30 rotating member, a spring attached to one 35 of said levers the system of levers being adapted to have movement imparted thereto against the action of the spring through the travel of the rotating member, a projection from the lever system whose radius of travel 40 at certain speeds will cause the same to engage the projection of the stationary member and at other speeds to cause these projections to miss each other, and an ignition system controlled thereby.
- 45 3. A speed governor for internal combustion engines including a compound lever system arranged to rotate about a fixed center, said system comprising a pivoted and weighted arm, a spring attached thereto in 50 opposition to the weight, a lever pivoted at one end, and a link connecting the lever and

arm, said lever, link and arm all being located on the same side of the center of rotation.

4. In speed governors, a rotative member, 55 an arm pivoted between its ends to said member, a weight and a spring acting on said arm at opposite sides of the pivot, a lever also pivoted at one end to the rotative member, a link connecting the free end of said 60 lever to the weighted arm, on the side of the pivot of the arm opposite the weight and a projection from such lever adapted to change its radial position under variations of speed of the rotative member 65 whereby a relatively large movement of the weight produces reduced movement of the free end of the lever.

5. In speed governors for internal combustion engines a rotating member carrying 70 a system of compound levers comprising an arm of the first and lever of the second order, both pivotally supported by the rotating member, a weight at one side and a spring at the other side of the arm, a link 75 connecting the free end of the lever to the arm between its pivot and the spring, and a tripping projection extending from the lever between its pivotal point and the link, whereby a maximum change of position of 80 the weight against the tension of the spring due to the movement of the rotating member the tripping projection will be moved a minimum distance.

6. In speed governors for internal combustion engines, a rotating member carrying 85 a system of compound levers comprising an arm pivoted between its ends, a lever pivoted at one end, a common support for both attached to the rotating member, a tripping 90 projection on the lever between its pivot and free end, a weight at one side and a spring at the other side of the pivotal point of the arm, and connecting means between the arm and lever whereby the direction of travel of the 95 weight against the tension of the spring under the movement of the rotating member is opposite to that of the tripping projection with respect to the center of rotation.

In testimony whereof I affix my signature.

JULIUS A. ZUEHLKE.
